(57) **CLAIM**

The ornamental design for a robotic dog, as shown and described.

DESCRIPTION

FIG. 1 is a perspective view of a first embodiment of the robotic dog of the instant invention;

FIG. 2 is another perspective view thereof;

FIG. 3 is a top plan view thereof;

FIG. 4 is a bottom view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a perspective view of a second embodiment of the robotic dog of the instant invention;

FIG. 10 is a top plan view thereof;

FIG. 11 is a bottom view thereof;

FIG. 12 is a front elevational view thereof;

FIG. 13 is a rear elevational view thereof;

FIG. 14 is a right side elevational view thereof; and,

FIG. 15 is a left side elevational view thereof.

The portions shown in broken lines are for illustrative purposes only; and form no part of the claimed design.
